UNITED STATES PATENT OFFICE.

STANLEY D. LIVINGSTON, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

ELECTRIC-SWITCH LOCK.

1,339,267.

Specification of Letters Patent.

Patented May 4, 1920.

Application filed September 30, 1919. Serial No. 327,422.

To all whom it may concern:

Be it known that I, STANLEY D. LIVINGSTON, a citizen of the United States of America, residing at Meriden, Connecticut, have 5 invented a new and useful Electric-Switch Lock, of which the following is a specification.

My invention relates particularly to a construction intended for use with ignition 10 and lighting systems.

The main object is to provide a simple and inexpensive form of construction in which the opening and closing of the circuit is controlled by a key.

15 Figure 1, is a plan view of a construction embodying the improvements of my invention. The key is shown in full lines in the position it would occupy when fully inserted for closing the circuit and in dotted lines 20 in the closed circuit position from which the key cannot be withdrawn without opening the circuit.

Fig. 2, is a horizontal sectional view of the parts in the open circuit position.

25 Fig. 3, are plan and side views respectively of a movable member of the lock which also serves to close the circuit.

Fig. 4, is a front view of the construction, the key being omitted.

30 Fig. 5, shows the shape of the key.

Fig. 6, shows the details of the lock spring.

The plate 10 which may constitute the 35 face plate, has an opening 11 shaped like the letter H with the upper and lower tongues 12, 12.

The movable member shown in Fig. 3, has a body 13 adapted to move between the adjacent ends of the tongues 12, 12. The 40 flanges 14 are of slightly less height than the sides of the H-shaped opening 11 and are adapted to turn through the slots about an axis, the flanges and the walls of the slot in the face plate acting as relative bearing 45 faces. For convenience in manufacture, the movable member may be formed of two separate parts secured together in any suitable manner as indicated in Fig. 3.

The spring 15 secured to the plate 10 is 50 provided with a locking tongue 16 which is adapted to fit into the recess 17 in the member 13 when the parts are in the position shown in Fig. 2 so as to lock the member 13 in position. The key 18 is adapted to be inserted into the slot 14' and has one or more

prongs such as 18' adapted to engage a tip 19 of the spring 15 so as to retract the locking tongue 16 from the recess 17 and permit the member 13 to be oscillated. The key is provided with a slot 20 which allows 60 for the thickness of the body of the member 13 and with slots 21 to allow for the tongues 12, 12 when the key is swung toward the right. The shank 22 of the key is of course 65 of proper width to pass between the adjacent ends of the tongues 12, 12. These tongues it will be noted are located a little to the right of the center of the opening 11 so that room enough is provided on the left to permit the key to be inserted but so that 70 the notches 21 will still be interlocked with the tongues 12, 12 when the key is swung to the right and it will then be impossible in the latter case to withdraw the key. The flange 14 may be provided with a shoulder 75 23 adapted to co-act with the tongue 16 when the key is swung to the right to limit the movement.

When the construction is used in a switch suitable contacts such as 24 and 24' may 80 be mounted in the chamber 25 of the housing 26 and adapted to be forced into contact with each other by an insulating button 27 on the tip of the swinging member 13. The upper and lower walls 28 of the 85 chamber 25 may serve to guide the tip 27 as the key is operated to swing the member 13.

I claim:—

1. In a lock, a plate having an H-shaped opening, an oscillating member having a 90 curved flange fitting in said opening and having a key slot, a locking member co-acting with the oscillating member and a key for inserting in said slot retracting said locking member and turning said oscillating member.

2. In a lock, a plate having an opening with a tongue projecting into the opening between the two sides thereof, an oscillating member having a body fitting in the opening opposite said tongue and having curved flanges fitting in the sides of said opening, a locking member co-acting with said oscillating member and a key adapted to be inserted through the flange of said oscillating member and having a tip to release said locking member and having a slot to allow for the swinging of said key past said tongue.

3. In a lock, a plate, an oscillating mem- 110

- ber pivotally carried thereby and having an opening for a key accessible through said plate, a spring adapted to interlock in said oscillating member and having an extension 65 in line with said key opening.
4. In a lock, a plate having an opening with oppositely disposed tongues intermediate the sides, an oscillating member pivotally carried by said plate adjacent said 70 tongues and provided with a key hole, a locking member co-acting with said oscillating member and a key for engaging said locking member, said key having slots to allow clearance past said tongues.
- 10 5. In a lock, a plate having an opening with oppositely disposed tongues intermediate the sides, an oscillating member pivotally carried by said plate adjacent said 75 tongues and provided with a key hole, a locking member co-acting with said oscillating member and a key for engaging said locking member, said key having slots to allow clearance past said tongues, said tongues being located nearer to one side of 80 the opening than the other so as to permit the key to be introduced when the oscillating member is swung to one extreme but to prevent the withdrawal of the key when the oscillating member is swung to the extreme opposite position.
- 15 6. In a lock, a plate having openings with tongues extending toward each other from opposite sides of said opening, an oscillating member having curved flanges guided 85 around said tongues and having a slot for the reception of a key, a locking member co-acting with said oscillating member and a key adapted to be inserted in said oscillating member for releasing said locking 90 member and swinging the oscillating member.
- 20 7. In a lock, a plate having oppositely disposed tongues, an oscillating member having curved flanges co-acting with said 95 tongues, a locking member co-acting with said oscillating member, a key for retracting said locking member and swinging said oscillating member, a spring member for yieldingly holding said oscillating member in one 100 position, a housing for said member and for said oscillating member, said housing having upper and lower walls limiting the movement of the inner end of said oscillating member.
- 25 8. In a lock, a housing, a spring member mounted therein, a front plate for said housing, an oscillating member pivotally carried by said front plate and having its rear end adapted to engage said spring member when 105 in one position and having a key slot accessible at the front of said oscillating member, a spring-pressed locking member co-acting with said oscillating member to hold it in one position, and a key adapted to be 110 inserted in the slot in said oscillating member for retracting said locking member and swinging said oscillating member to engage said spring member.
- 30 9. In a lock, a plate having an opening with a lug projecting into one side thereof, a member having a body extending through the center of said opening and having a flange surrounding one side of said lug said member having a key slot intersecting the plane of the opening, a latch for said member in line with said slot when said member is in one position, the plane of said slot intersecting said lug when said member is in another position.
- 35 10. In a lock, a plate having an H shaped opening, a member pivoted in said opening and having a key slot whose plane intersects the plane of said opening, a latch in line with said key slot when said member is in one position, and a key for retracting 85 said latch.
- 40 11. In a lock, a body member having semi-circular flanges and a key slot intersecting said flanges, means for pivotally supporting said member, a spring pressed latch for holding said member in one position, said latch having a portion extending in line with said slot when the parts are in the latched position.
- 45 12. In a lock, a pivoted body member having curved flanges and a slot intersecting said flanges and said body, a spring pressed latch for holding said body in one position, and a bifurcated key for retracting said latch and having notches in its edges corresponding with said flanges.
- 50 13. In a lock, an oscillating member having a key slot, a supporting member for said oscillating member having a key passage, a spring-pressed latch for engaging said oscillating member to hold it in one position, a key adapted to be inserted in the slot in said oscillating member, said key having a notch in its outer end to enable it to clear a part of said oscillating member and having a notch in one edge to enable it to clear a part 105 of said supporting member, said key being adapted to retract said latch and to swing said oscillating member when said latch is retracted, and means co-acting with said key 110 to prevent its withdrawal when said oscillating member has been swung from its latched position.
- 55 14. In a lock, a plate having an H shaped opening, a member having semi-circular flanges pivotally mounted in said opening and having a key slot and a latch co-acting with said member to hold it in one position and having a portion projecting in line with said slot when said member is in said 120 position.

STANLEY D. LIVINGSTON.
